UNITED STATES PATENT OFFICE.

THOMAS R. JENKINS, JR., OF BALTIMORE, MARYLAND, ASSIGNOR OF ONE-HALF TO MILTON C. GREER, OF BALTIMORE, MARYLAND.

FLUSHING-VALVE.

No. 909,605.

Specification of Letters Patent.

Patented Jan. 12, 1909.

Application filed December 31, 1907. Serial No. 408,761.

To all whom it may concern:

Be it known that I, THOMAS R. JENKINS, Jr., a citizen of the United States, residing at Baltimore, in the State of Maryland, 5 have invented certain new and useful Improvements in Flushing-Valves, of which the following is a specification.

This invention relates to improvements in flushing valves and has particular reference 10 to a valve suitable for use in flushing water closets in that upon being operated the valve will permit sufficient water to flow through the closet to flush the latter and then automatically cut off such flow of water.

One object of the invention is to provide 15 an improved construction of valve of this character which may be readily connected direct between the water-supply and the closet and avoid the use of a storage tank, thus eliminating the expense incident to the 20 installation and maintenance of the tank and its fittings as well as their objectionable features from a sanitary point of view.

Another object of the invention is to provide 25 a flushing valve of such improved construction as to enable its entire interior working parts to be withdrawn from the casing upon the removal of a single part and thereby permit a ready inspection, 30 cleaning or repairing of such parts.

Another object is to improve the construction of such valves so as to make them sensitive in operation and permit of delicate adjustment in regulating the length of the 35 flushing period.

Another object is to construct a valve that will avoid a thumping or hammering noise at the moment of cutting-off the water supply, and a further object is to generally improve 40 the construction of valves of this class; to cheapen their cost and manufacture and make them practically indestructible in ordinary use.

The invention is illustrated in the accompanying drawing, in which,—

Figure 1, shows a plan view of the improved valve. Fig. 2, illustrates a central vertical sectional view through the same. Fig. 3, shows a horizontal cross-sectional view 50 through the valve,—the section being taken on the line 3—3 of Fig. 2, and Fig. 4 illustrates a similar cross-sectional view through the valve—this section however being taken on the line 4—4 of Fig. 2.

Referring to the several views of the

drawing, the numeral, 1, designates the outer shell or valve casing having a water-supply connection, 2, at its lower end; a horizontal water-supply passage, 3, extending inwardly toward the center of the casing 60 from the supply connection and a port, 4, in one side of said passage through which water may pass direct to the closet, as will presently appear. A chamber, 5, is provided in the casing at the side of the water-supply passage, and the port, 4, when uncovered, establishes communication between the chamber and said supply passage. The casing is also provided with a vertical passage, 6, which extends from the chamber, 5, 70 and at the lower end of this passage the casing is provided with exterior screw-threads, 7, by means of which said vertical passage may be made to communicate with the closet bowl, or a pipe leading thereto, 75 which it is deemed unnecessary to illustrate.

The upper portion of the casing is provided with an equalizing chamber, 8, of a general circular form which is provided with a port, 9, in its bottom, 10. The port, 80 9, in the bottom of the equalizing chamber has position directly over the supply port, 4, but is of a greater diameter than said supply port.

A cylindrical valve, 11, has position in the 85 equalizing chamber and is provided with a depending central threaded stem, 12, which projects from the bottom surface thereof and around which a suitable washer, 13, is placed. This washer is held in place against the bottom of the cylindrical valve by means of a metal washer, 14, and a nut, 75, which fit over and engage the threaded stem, 12. The stem, 12, projects down into the port, 9, in the bottom of the equalizing chamber while 90 the washer, 13, seats around and closes the said port.

The cylindrical valve, 11, is provided with a plurality of laterally-projecting side lugs, 15, which are spaced apart and which contact with the circular wall of the equalizing chamber, as seen particularly in Fig. 3, so as to prevent lateral displacement of the valve during vertical movement thereof.

By reference to Fig. 2, it will be seen that 105 a vertical flange, 16, surrounds the port, 9, and projects upwardly from the bottom, 10, of the equalizing chamber and thus the seat for the cylindrical valve is elevated above the bottom of said equalizing chamber. By 110

this construction the liability of the lodgment on the valve seat, of dirt or other particles and leaking of the valves as the result thereof will be avoided.

5 The cylindrical valve, 11, is open at its upper end so that the interior of said end will always be in communication with the equalizing chamber, and at this open upper end said valve is provided with a horizontal 10 cross-bar, 17, with circular central recesses, 18, and, 19, at the upper and lower sides thereof. This cross-bar, 17, is also provided with a central vertical stem, 20, which projects upwardly above the open end of the 15 valve and enters a vertical chamber, 21, in a stem, 22, that is integral with and depends from a screw cap, 23, that serves to close the upper end of the equalizing chamber. The vertical stem, 20, at the upper end of the 20 cylindrical valve and the lateral lugs, 15, adjacent the lower end serve to maintain the valve in a position central with respect to the ports, 4, and, 9, but permit said valve to have a vertical movement in the equalizing 25 chamber.

25 A spiral spring, 24, has its lower end seated in the upper circular recess, 18, on the cross-bar and its upper end encircles the stem, 22, on the screw-cap, 23. This spring by pressing downwardly on the cross-bar serves to 30 keep the cylindrical valve seated over the port, 9, and counter-balances the weight of the operating lever and the tendency of the latter to raise said valve as will presently be 35 fully described.

The interior chamber, 25, of the cylindrical valve is provided with a piston, 26, which, in the present instance is of a suitable 40 flexible material and of a cup-shape. This piston is provided with a central vertical stem, 27, whose upper end projects through the piston and carries washer plates, 28, and, 29, at opposite sides of the piston while nuts, 30, on the upper end of said stem secure the 45 latter with respect to the piston. The lower end of the stem, 27, extends through the closed end of the cylindrical valve and also through the threaded stem of said valve; the extreme end of the piston stem carries a 50 metal disk or head, 31, and a washer or disk valve, 32, which latter seats down on and covers the port, 4, of the water-supply passage. A groove, 33, extends vertically along the piston stem and forms a vent passage 55 from the cylindrical valve chamber below the piston, which vents into the chamber, 5. By providing this vent passage the space on the under side of the piston, 26, is kept free from pressure that would hinder the piston 60 from making its downward stroke and will admit air in said space from the chamber, 5, when the piston makes its upward stroke and thereby enables the piston to readily move up or down when it is called upon to 65 make either of its strokes.

In order to provide for a slight preponderance of pressure on the upper side of the piston, during such times as it is desired to keep the valve, 32, seated around the port, 4, I interpose a light spiral spring, 34, between 70 the piston and the recess, 19, in the bottom of the cross-bar, 17.

A branch water-supply passage, 35, is provided in the valve casing, 1, which branches from and is always in communication with the main supply-passage, 3. This branch passage is provided at its upper end with a port, 36, having a conical seat which port opens into the equalizing chamber, 8, at the side of the cylindrical valve. A needle 80 valve, 37, is fitted into the side of the valve casing with its tapered end in line or in register with the port, 36, while the end of said needle valve passes through a stuffing box, 38, and is provided with a head, 39, 85 at its outer end. By means of this needle valve and the port, 36, the flow of water from the branch passage, 35, into the equalizing chamber may be controlled so as to effect a filling of the equalizing chamber 90 slowly or rapidly as desired.

By reference to Figs. 2 and 4 it will be seen that the cylindrical valve, 11, is provided at its upper end with a side lug, 40, and that adjacent to said lug the side of the 95 valve casing is provided with an outwardly-extending curved recess, 41, with a lateral side extension or barrel, 42. An operating shaft, 43, extends through a stuffing box, 44, at the end of the barrel and has 100 a reduced circular end, 45, which fits into and has bearing in a circular recess, 46, in the wall, 47, at the side of the curved recess. Adjacent the circular bearing-end the operating shaft is provided with a squared 105 or angular portion, 48, on which a circular body, 49, is rigidly mounted. This body is provided with an arm, 50, which extends laterally therefrom and projects beneath the lug, 40, on the cylindrical valve, 11. An operating arm, 51, at the end of the shaft, 43, enables the latter to be readily rocked or depressed, while a lug, 52, on the arm, 50, serves to prevent the operating arm from being elevated above its correct normal position.

Two washer plates, 53, and, 54, have position on the shaft, 43, at the side of the body, 49,—the plate, 54, being held frictionally 110 against the washer, 53, by the packing material in the stuffing box.

In the operation of the device the passages, 3, and, 35, are always filled with water, being in direct communication with the water supply pipe, and the needle valve, 37, is so adjusted as to provide a restricted 125 passage for water through the port, 36, into the equalizing chamber. Normally, and when ready for operation, the water pressure in the passages, 3, and, 35, and also in 130

the chamber, 8, are equalized and the ports, 4, and, 9, are closed. To flush the closet the arm, 51, is depressed and immediately released and the depressing of said arm causes a slight rotation of the shaft, 43; raises the arm, 50, and lifts the cylindrical valve, 11, to momentarily uncover the port, 9. The lifting of the valve, 11, also causes a slight elevation of the valve, 32, from the port, 4, and as both the ports, 4, and, 9, are manually uncovered a quantity of water from the equalizing chamber will escape and thus reduce the pressure in said chamber below the pressure in the passage, 3. This lowering of the pressure in the equalizing chamber causes the preponderance of pressure in the passage, 3, to act on the under side of the valve, 32, and elevate it sufficiently to permit the water in the supply passage, 3, to pass through the port, 4, freely and thence through passage, 6, to the closet. Although the cylindrical valve immediately drops and closes the port, 9, upon releasing the operating arm, 51, the piston, 26, stem, 27, and valve, 32, remain elevated until the downward pressure on the piston, caused by the refilling of the equalizing chamber with water that flows through port, 36, is sufficient to cause a downward stroke of the piston and its stem. To enable this to be readily accomplished without contending with pressure on the bottom side of the piston I provide the vertical groove, 33, in the piston stem through which air may be expelled or admitted when the piston is making its strokes.

It is found that a valve constructed like that herein shown and described operates with reliability and is free of noise and that the removal of the cap, 23, permits immediate access to all the working parts.

Having thus described my invention what I claim and desire to secure by Letters Patent is,—

1. In a flushing valve, a casing having a water-supply passage with a port, an equalizing chamber also with a port, and an outlet passage, a cylindrical valve movable vertically in the equalizing chamber to control the port thereof, a valve depending from and movable independently of said cylindrical valve and operated by variations of pressure in said movable cylindrical valve, and means whereby the cylindrical valve may be operated to cause a variation of pressure therein.

2. In a flushing valve, a casing having an

upper equalizing chamber with a port, a lower water-supply passage also with a port and an outlet passage between said chamber and supply passage, a cylindrical valve movable vertically in said chamber with respect to the port thereof, a piston in said cylindrical valve and having movement independently of the latter, a stem operated by the piston, a valve carried by the stem to control the port of the supply passage, and means for operating the cylindrical valve to reduce the pressure on the interior thereof.

3. In a flushing valve, a casing having a water-supply passage with a port, an equalizing chamber also with a port, and an outlet passage between the two ports, a water-supply for said equalizing chamber, a valve movable in said equalizing chamber, a piston also in the equalizing chamber and movable with respect to and independently of said valve, said piston having a stem that extends through said valve, a valve on the lower end of said stem to control the port of the water-supply passage, and means for manually lifting the valve in the equalizing chamber.

4. In a flushing valve, a casing having a water-supply passage with a port, an equalizing chamber also with a port and an outlet passage between said supply-passage and said chamber, a cylindrical valve movable vertically in said chamber, a piston in said cylindrical valve, a stem carried by said piston, a valve on said stem to control the port of the supply passage, means for venting the space in the cylindrical valve beneath the piston, and means for operating said cylindrical valve.

5. In a flushing valve, a casing having a water-supply passage with a port, an equalizing chamber also with a port, an outlet passage between said supply passage and chamber, a water-supply for said equalizing chamber, a cylindrical valve in said equalizing chamber, a piston in said cylindrical valve and having a stem that extends through said valve, a valve on the end of said stem, means for yieldingly pressing the cylindrical valve down; means for yieldingly pressing down on the piston, and means whereby the cylindrical valve may be manually operated.

In testimony whereof I affix my signature in presence of two witnesses.
